(57) **CLAIM**

The ornamental design for a battery, as shown and described.

DESCRIPTION

FIG. 1 is a perspective view of a battery showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is an enlarged cross sectional view along the lines 8-8 of FIGS. 2 and 6; and

FIG. 9 is an enlarged cross sectional view along the lines 9-9 of FIGS. 2 and 6.

FIG. 10 is a perspective view of another embodiment of a battery showing our new design;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and

FIG. 16 is a bottom plan view thereof.

FIG. 17 is an enlarged reference cross sectional view along the lines 17-17 of FIGS. 11 and 15; and

FIG. 18 is an enlarged reference cross sectional view along the lines 18-18 of FIGS. 11 and 15.

FIG. 19 is a perspective view of still another embodiment of a battery showing our new design;

FIG. 20 is a front elevational view thereof;

FIG. 21 is a rear elevational view thereof;

FIG. 22 is a left side elevational view thereof;

FIG. 23 is a right side elevational view thereof;

FIG. 24 is a top plan view thereof; and

FIG. 25 is a bottom plan view thereof.

FIG. 26 is an enlarged reference cross sectional view along the lines 26-26 of FIGS. 20 and 24; and,

FIG. 27 is an enlarged reference cross sectional view along the lines 27-27 of FIGS. 20 and 24.
